(57) CLAIM

The ornamental design for a frozen dessert machine, as shown and described.

DESCRIPTION

FIG. 1 is a top, front, and side perspective view of an embodiment of a frozen dessert machine embodying my new design.

FIG. 2 is a front view thereof.

FIG. 3 is a back view thereof.

FIG. 4 is a first side view thereof.

FIG. 5 is a second side view thereof.

FIG. 6 is a top view thereof; and,

FIG. 7 is a bottom view thereof.

Broken lines are used to illustrate features of the frozen dessert machine which form no part of the presently claimed design.
